UNITED STATES PATENT OFFICE.

EDWIN F. HULBERT, OF OWEN, WISCONSIN, ASSIGNOR TO THE MASTER PACKAGE CORPORATION, OF OWEN, WISCONSIN, A CORPORATION OF DELAWARE.

CONTAINER.

Application filed March 14, 1927. Serial No. 175,259.

The invention relates to containers and more particularly to a reinforced fibre or paper container.

The object of the invention is to provide an end closure for the container wherein the mouth thereof is provided with a beaded or rounded edge by the association of the siding of the container with a metal band and the removable cover is provided with a metal band having a flanged portion extending over the mouth and bendable beneath the rounded edge either entirely around the container or at spaced intervals.

The invention further consists in the several features hereinafter set forth and more particularly defined by claims at the conclusion hereof.

In the drawings Fig. 1 is an elevation view of a container embodying the invention, parts being broken away and parts being shown in section;

Fig. 2 is a top view of the container;

Fig. 3 is an enlarged detail sectional view through a container embodying the invention, with the cover in position for attachment;

Fig. 4 is a view similar to Fig. 3 with the cover affixed to the body;

Fig. 5 is a view similar to Fig. 3 showing a modified form of cover in position for attachment;

Fig. 6 is a view similar to Fig. 5 with this cover in affixed position.

The siding or body 7 of the container is composed of fibre tubing, usually made up of a number of wrappings of paper or fibre sheets into a cylindrical or conical form.

For forming a reinforcement and a rounded or beaded cover-attaching portion at the mouth of the container, a strip of sheet metal, preferably sheet steel, is rolled into a band 8 and affixed to the upper edge of the siding of the container by pressing the inner edge 9 of the band into the wall of the container and bending the upper portion 10 of the band over the upper edge of the container and forcing the outer edge 11 of this bead or curved portion 12 of the band into engagement with the siding, thereby forming a metal-sheathed mouth having a cover-attaching bead.

The head or cover structure comprises a fibre disk 13 and a metal sheathing or band 14, preferably of thin sheet steel or other

suitable sheet metal, is designed to clamp- 55 ingly receive said disk.

The band 14, in each instance, has a folded-together portion intermediate its top and bottom edges forming a flange 15 upon which the bottom of the head seats and its upper edge 16 is bent over into clamping engagement with the head whereby the head, adjacent its outer edge, is firmly held or clamped within the recess thus formed, the strip forming the band being bent around 65 the head with its ends secured together in any suitable manner, the bending of the top edge preferably being done when the head is in position within the band. The lower portion 17 of the band depends from the flange 15 and may be plain as shown in Figs. 1, 3 and 4, or its lower edge 18 may be beaded as shown in Fig. 5, to stiffen and strengthen it.

The depending portion 17 of the band is 75 preferably of a diameter to make a good fit over the metal-faced mouth of the pail, as shown in Figs. 3 and 4, and in applied position the flange 15 abuts against the metal band 8.

With the cover applied as shown in Figs. 3 and 4 the same is affixed to the pail body by bending portions 19 of the flange or depending portion 17 inwardly around the beaded edge 12 of the band 8, thus forming 85 a metal-to-metal interlocking connection between the cover and the pail body. As shown in Figs. 1 and 2 the flange 17 is crimped or bent over the bead 12 at spaced intervals but if desired the whole flange may 90 be so treated. In either case the cover is securely locked to the body and tampering with the contents of the container cannot be effected without detection since a prying out of the flange 17 from its locked position 95 and an attempt to bend these pried out parts back will be noticed and the bending of the flanges cannot be done with ordinary tools.

It will be noted that the flange 15 rests on the upper part of the band 8 when the cover is attached and that this construction provides wear-resisting surfaces and insures a good seal. Furthermore, the upwardly projecting or arched portion 20 of the cover band assists the attaching tools in securing a 100 firm grip on the cover during the cover-affixing operation.

I desire it to be understood that this is

vention is not to be limited to any particular form or arrangement of parts except in so far as such limitations are included in the claims.

5. What I claim as my invention is:

1. In a container, the combination with the siding, of a metal band for the mouth of said container having a portion extending around the inner wall of the siding adjacent its edge and around said edge into crimped engagement with the outer side of said siding to form a head-attaching bead and having its inner edge in embedded engagement with the inner side of said siding,
- 10 15 a removable cover including a reinforcing and head-attaching band fitting over said first-named band and bendable over the lower part of said bead to a head-affixing position and having a folded intermediate portion forming an inwardly extending flange adjacent its upper edge adapted to abut against the top of said first-named band, and a head member seating on said flange and clamped thereto by the upper edge of said head-attaching band pressed into contact therewith.
- 20 25 30 2. In a container, the combination with the siding, of a metal band for the mouth of the container having a portion extending around the inner wall of the siding adjacent its edge and around said edge into crimped engagement with the outer side of

said siding to form a head-attaching bead and having its inner edge in embedded engagement with the inner side of said siding, 35 a removable cover including a fibre head and a metal band having spaced portions between which the outer edge of the head is clamped and provided with a depending portion having parts bent into interlocking engagement with said head-attaching bead. 40

3. In a container, the combination with the fibre siding, of a metal band secured to the mouth thereof and having an external annular head-attaching bead, a removable cover having a fibre head and a band clamped thereto and provided with a depending portion fitting over said mouth and engageable with said bead in a head-affixing position. 45

4. In a container, the combination with the siding, of a metal band for the mouth of the container having a portion extending around the inner wall of the siding adjacent its edge and around said edge into crimped engagement with said siding, a removable cover including a fibre head and a metal band having spaced portions between which the outer edge of the head is clamped, said cover band also having a depending flange having interlocking engagement with said metal mouth band. 55 60

In testimony whereof, I affix my signature.
EDWIN F. HULBERT.
